[57] CLAIM

The ornamental design for a compact chair-tilting control, as shown and described.

DESCRIPTION

FIG. 1 is a top plan view of a compact chair-tilting control showing our new design.

FIG. 2 is a side elevational view thereof.

FIG. 3 is a front view thereof.

FIG. 4 is a rear view thereof.

FIG. 5 is a bottom view thereof.

The appearance of the side opposite that shown in FIG. 2 is a mirror image to FIG. 2.
